UNITED STATES PATENT OFFICE.

OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

BACK-SPACING MECHANISM FOR PAPER-CARRIAGES.

1,096,074.

Specification of Letters Patent.

Patented May 12, 1914.

Application filed April 7, 1913. Serial No. 759,495.

To all whom it may concern:

Be it known that I, OTTO THIEME, a citizen of the United States, residing at the city of St. Louis, State of Missouri, have invented 5 a certain new and useful Improvement in Back-Spacing Mechanism for Paper-Carriages, of which the following is a full, clear, and exact description, such as will enable others skilled in the art to which it appertains to make and use the same, reference being had to the accompanying drawings, forming part of this specification, in which—

Figure 1 is a rear elevational view of my 15 improved back spacing mechanism. Fig. 2 is a side elevational view of the same. Fig. 3 is a rear elevational view. Fig. 4 is a detail view of the clutch. Fig. 5 is a top plan view of the tappet. 20 This invention relates to a new and useful improvement in back spacing mechanism for paper carriages of combined typewriting and calculating machines, such for instance as that shown in Belgian patent granted to 25 Hubert Hopkins August 21st, 1907, No. 202,081, and French Patent No. 383,719, dated January 16, 1908.

In an application filed by me August 7th, 1911, Serial Number 642,888, I have described the details of a carriage return mechanism part of which is herein illustrated and will therefore not give a detailed description of the same here, further than to say that the constantly running motor, not 35 shown, drives a pinion 1 mounted on shaft 2 which, through suitable motor gears, rotates a shaft 3 on the upper end of which is a clutch mechanism 4 whereby, when said clutch mechanism is raised by means of a 40 lever 5, the escapement shaft 6, having pinion 7 on its upper end in mesh with rack 8 on the paper carriage, will be driven so as to move the carriage to its starting position at the right hand side of the machine. 45 Lever 5 is engaged by a rod 9 to a carriage return key 10 whereby the carriage return mechanism may be rendered effective by manual depression of said key.

It is the object of my present invention to 50 provide means whereby, when the carriage reaches a certain position in its leftward movement, a block 13 adjustably mounted thereon will mechanically set in operation the carriage return mechanism, whereby the 55 carriage will be back spaced a few spaces

without requiring the operator to depress the key 10.

To carry out the objects of my invention, I arrange a tappet 14 in the path of movement of the block, which tappet is so mounted on the upper end of lever 15 that when the carriage is moved leftwardly, it will rock lever 15 rearwardly and by means of the extension 16 of said lever, which is fixed thereto, and rod 17 connected to the end of extension 16, a plate 18 will be swung rearwardly. A spring 19 connects this plate with the upper end of a lever 20 pivotally mounted on the key 10 so that said upper end of lever 20 will be caused to follow the plate 25 when the levers 15—16 are rocked. The lower end of lever 20 terminates in a hook and when this lower hooked end swings forwardly, it will engage a pin 21 on the end of a rock arm 22 mounted on rock shaft 23 secured in a suitable bracket plate secured under the bed plate of the machine, and which rock shaft carries a rock arm 24 at its opposite end provided with a roller 25 yieldingly held against the periphery of a 30 cam 26 mounted on the rotating shaft 2 by means of a spring 27. The arm 22 is caused to vibrate by means of a cam 26 and when the hooked lever 20 is disengaged therefrom, such vibration is, of course, idle; but 35 when the hooked end of lever 20 is moved into engagement with the pin 21, the vibration of arm 22 will depress the key lever 10 and set the back spacing mechanism into 40 operation, moving the carriage. The length of the periphery of the enlarged portion of the cam 26 determines the back spacing movement of the carriage, and while, for 45 purposes of the machine disclosed, it is only necessary to back space the carriage about 95 three notches in the particular class of tabulating work for which it was designed, it is obvious that the enlarged portion of the cam 26 can be increased circumferentially so as to impart a greater back spacing movement 50 to the carriage. When the enlarged portion of cam 26 passes from the roller the pin 21 starts to rise and will release the hooked end of lever 20, as is obvious. This back spacing mechanism is designed particularly 55 for use in connection with totalizer selecting and controlling mechanism disclosed in a companion application filed by me of even date herewith, Serial No. 759,493, with 60 which it is also desirable to use the automatic 65

100 carriage return mechanism. 75

tabulating mechanism disclosed in a companion application filed by me of even date Serial No. 759,494.

What I claim is:

- 5 1. A back spacing mechanism for machines of the character described comprising in combination with an escapement mechanism shaft, a constantly running shaft, a clutch for engaging said shaft with
10 said escapement mechanism shaft, manually operable means for operating said clutch, and means controlled by the paper carriage for operating said clutch when said carriage reaches a certain position.
- 15 2. In a back spacing mechanism for machines of the character described, the combination of a paper carriage, an escapement mechanism shaft, a constantly rotating shaft, a clutch for engaging said shaft with
20 said escapement mechanism shaft for back spacing the carriage, and means controlled by the paper carriage for rendering said back spacing mechanism effective.
- 25 3. In a back spacing mechanism for machines of the character described, the combination of a paper carriage, an escapement mechanism shaft, a constantly rotating shaft, a clutch for engaging said shaft with
30 said escapement mechanism shaft for back spacing the carriage, and means controlled by the paper carriage for rendering said back spacing mechanism effective, said means being mechanically driven together with said constantly rotating shaft, and the
35 length of said back spacing movement being controlled by said mechanically driven means.
4. The combination with a paper carriage for machines of the class described, an escapement mechanism shaft, a constantly rotating shaft, a clutch for engaging said constantly rotating shaft and said escapement mechanism shaft whereby a spacing is effected, means for operating said clutch, and means on the carriage for operating said clutch operating mechanism, said clutch operating mechanism including in its train devices which control the back spacing movement of the carriage.
- 45 5. The combination of a laterally movable paper carriage for machines of the class described, an escapement mechanism shaft, a constantly rotating shaft, a constantly rotating cam, a clutch for engaging said shaft with said escapement mechanism shaft, and
50 means for operating said clutch to effect such engagement, said cam holding said clutch in such engagement during a predetermined portion of its revolutions.
- 55 6. The combination of a paper carriage for a machine of the class described, an escapement mechanism shaft, a constantly rotating shaft for back spacing said carriage, a constantly rotating cam, and means for rendering said cam effective to cause the carriage to be back spaced.

In testimony whereof I hereunto affix my signature in the presence of two witnesses, this 2nd day of April, 1913.

OTTO THIEME.
